UNITED STATES PATENT OFFICE

168,929

CASING FOR A SEWING MACHINE

Arthur Leo Foyar, San Francisco, Calif.

Application July 21, 1952, Serial No. 20,697
In Japan May 23, 1952

Term of patent 14 years

(Cl. D70—1)

To all whom it may concern:

Be it known that I, Arthur Leo Foyar, a citizen of the United States and a resident of the city and county of San Francisco, State of California, have invented a new, original, and ornamental Design for a Casing for a Sewing Machine, of which the following is a specification, reference being had to the accompanying drawings, forming a part hereof:

Fig. 1 is a front elevational view of a casing for a sewing machine, showing my new design;

Fig. 2 is a rear elevational view of a casing for a sewing machine showing my new design;

Fig. 3 is a side elevational view thereof viewed from the left;

Fig. 4 is a side elevational view thereof viewed from the right;

Fig. 5 is a top plan view of a casing for a sewing machine showing my new design.

I claim:

The ornamental design for a casing for a sewing machine, as shown.

ARTHUR LEO FOYAR.
